UNITED STATES PATENT OFFICE.

EDWARD D. PUTT AND HORACE D. STEVENS, OF AKRON, OHIO, ASSIGNEES TO THE FIRESTONE TIRE AND RUBBER COMPANY, OF AKRON, OHIO, A CORPORATION OF OHIO.

MACHINE FOR CUTTING FAN BELTS OR THE LIKE.

Application filed April 2, 1923. Serial No. 629,347.

This invention relates to machines adapted to cut rings or short cylinders from larger cylinders and is particularly designed and intended for cutting narrow belts such as 5 used in fans of automobiles, from large cylinders of rubberized and vulcanized fabric. While the machine is designed and built for the particular purpose specified, it will, of course, be apparent that it is not necessarily 10 narrowly limited to this purpose or function, but may be extended into other fields.

The object of the invention is to provide a 15 machine which will rapidly and accurately cut off belts from the cylinders of fabric and rubber in which form the belt stock is manufactured. The machine is simple in construction and operation and will perform the operations required of it without the necessity for skilled labor.

20 Other objects and advantages will be apparent as the description of the machine progresses; it being obvious that while the machine is described in detail sufficient to enable its construction and operation to be understood, the invention is not limited to such 25 details, but may be embodied in other forms and proportions.

In the drawings:

Figure 1 is a side elevation of the machine; 30 Figure 2 is a plan view;

Figure 3 is an end view;

Figure 4 is an enlarged view, partly in section, showing the cutter head withdrawn; and

Figure 5 is another view of the parts shown in Figure 4, but with the knife in action.

In the drawings, 1 represents a table or stand on which the operating parts of the 40 machine are supported, at the side of which is a standard 2. A motor 3 is mounted in a suitable position on the table driving a pulley 4 through a belt 5. The shaft 6 of pulley 4 carries a second pulley 7 which through a belt 8 drives a counter shaft 9 in the standard 2. A pinion 10 on the shaft 9 drives a large gear 11 which is secured to a shaft 12.

On the shaft 12 is mounted a one-revolution and stop clutch which may be of any 50 preferred design, and which will not be described in detail, being indicated by the numeral 13. The clutch comprises an operating pawl 14 which is engaged and released by a

pivottally mounted lever 15 which is actuated by a rock shaft 16 and foot treadle 17. 55

The treadle 17 is depressed by the operation at suitable intervals, which action serves to engage the clutch for a single revolution. On the clutch body is carried a crank 18 which is pivotally connected to a bell crank 60 lever 19 supported on the table. The lever 19 operates the cutter head as will be explained.

At the side of the table remote from the lever 19 is secured to a base plate 22 a rigid metal cylinder 20, the internal diameter of 65 which is slightly larger than the cylinder of rubber and fabric 21 so that the latter can be advanced through the cylinder as required. On the end of the base plate opposite the cylinder 20 are secured two brackets 70 23, and supported in these brackets and in bearings 24 extending from the cylinder 20, are parallel horizontal shafts 25 which support the cutter head.

The cutter head or carriage, which is indicated generally by the numeral 26, comprises 75 a frame 27 which is received between the rails 25 and is supported thereon by opposed pairs of rollers 28 which ride upon the rails 25. The carriage or cutter head supports a 80 motor 29; the pinion 30 of which engages a gear 31 secured to one end of a hollow shaft or sleeve 32 which is mounted in bearings in the frame 27.

On the forward end of the sleeve 32 or the 85 end near the cylinder 20, is keyed, as at 33, the knife head 34. This is shown in section in Figures 4 and 5 and in elevation in Figure 3. It comprises an arm, counterweighted on one side of the shaft 32, as at 35; and at the 90 other side of the shaft provided with a slot or recess 36.

In the slot 36 is slidably mounted a knife carrier 37 which is normally kept at the inner 95 end of the slot by a spring 38. Offset from the carrier is secured the knife or blade 39 and on the inside of the carrier is a roller 40. This roller is arranged to contact a rotary cam 41 which is pivoted in the knife head and is operated as will be described. 100

When the knife is projected outwardly by the operation of the cam at the proper moment in the working of the apparatus, it projects within the cylinder of fabric in the holder or cylinder 20, and is passed 105 around the inside of the cylinder by the rete-

tion of the shaft 32. A groove or slot 42 is cut on the inside of the cylinder 20 for the reception of the end of the knife blade.

The cam 41 is provided with a series of 5 gear teeth 43, which engage a rack 44 formed over the outer end of a longitudinally reciprocal rod 45 mounted in the sleeve 32. The rear end of the rod extends beyond the gear 31 and is provided with a cap 45^a between which and the gear is located an expansion spring 46. A head 47 on the rod, contacting the shaft 32, limits the inward movement of the rod. The end of the lever 19 bears on the cap 45^a. To the front of 15 the carriage 26 is secured a ring 48 which is arranged to contact the front end of the cylinder and stop the forward advance of the carriage and thus position the knife at the proper point with respect to the cylinder, 20 acting as a gage for determining the width of the fan belt. A strap 49 may be secured to the rear of the knife carriage and causes the lever 19 to withdraw the carriage as will be understood.

25 The operation of the apparatus is as follows. A cylinder of fabric and rubber or other material is placed within the cylinder 20 and is projected beyond the end of the cylinder. The interior of the cylinder 30 may be roughened slightly to prevent turning of the fabric therein. The carriage being withdrawn, as shown in Figure 1, the operator depresses the treadle 17 which engages the single operation clutch rocking 35 the lever 19. This exerts an inward movement on the rod 45, but the spring 46 is sufficiently strong so that the carriage will be moved forward without compressing the spring until the gage 48 strikes the end of 40 the cylinder 20. In the meantime the ring 48 has engaged the end of the cylinder of fabric and pressed it back until flush with the end of the cylinder, at which time also the knife head is within the cylinder with 45 the knife retracted at the line of the groove 42. The continued movement of the lever 19 now pushes the rod 45 forward and the rack 44 rotates the cam and projects the knife outwardly to perform the cut, the 50 knife head being rotated during the entire operation by the motor 29 at a sufficient rate of speed to enable the cut to be completed. The lever 19 is now withdrawn and the carriage moves backwardly to its open position. The cylinder of fabric is then pushed forwardly, discharging the cut fan belt down the delivery chute 50, and is ready for a new 55 cut.

60 It is obvious that changes and modifications may be made as desired. The machine is adaptable for rapid and satisfactory operation, and while it is shown as limited to one size of belt, it may be adjusted to belts of various thicknesses, as will be understood.

65 What we claim is:

1. In a machine for cutting belts or the like, a holder for supporting an uncut cylinder so as to be fed thereon, a reciprocating carriage movable toward and from the holder, and a rotary knife supported on said carriage.

2. In a machine for cutting belts or the like, a holder for supporting an uncut cylinder so as to be fed thereon, a knife carriage, a rotary knife supported on the carriage, and means to cause the holder and carriage to approach one another axially of the knife.

3. In a machine for cutting belts or the like, a holder for exteriorly supporting an uncut cylinder, a knife carriage, a knife supported on said carriage so as to be radially movable within the cylinder in the holder, means for moving the knife in a circular path, and means for projecting the knife into the cylinder.

4. In a machine for cutting belts or the like, a holder for supporting an uncut cylinder, a knife carriage, a knife supported on said carriage interiorly of the cylinder in the holder, means for moving the knife in a circular path, and means for projecting the knife outwardly into the cylinder in the holder.

5. In a machine for cutting belts or the like, a holder for supporting an uncut cylinder, a knife carriage movable toward and from said holder, a knife supported on said carriage and normally positioned interiorly of the cylinder in the holder, and means for projecting the knife outwardly of the carriage.

6. In a machine for cutting belts or the like, a holder for supporting an uncut cylinder, a knife carriage movable toward and from said holder, a knife supported on said carriage and normally positioned interiorly of the cylinder in the holder, means for projecting the knife outwardly of the carriage, and means for moving the knife in a circular path.

7. In a machine for cutting belts or the like, a support for a cylinder of material, a knife carriage movable toward and from said support, a continuously rotated head on said carriage, a knife on said head, and means for moving the knife radially of the head.

8. In a machine for cutting fan belts or the like, a support for a cylinder of material, a knife carriage movable toward and from said support, a continuously rotated head on said carriage, a knife on said head, and single operative means to move the carriage and then to move the knife radially of the head.

9. In a machine for cutting fan belts or the like, a support for a cylinder of material, a knife carriage movable toward and from said support, a stop for said carriage, a continuously rotated head on said carriage, a knife movable radially of the head, and a

single operative means to move the carriage until arrested by the stop and then to move the knife radially of the head.

10. In a machine for cutting fan belts or the like, a support for a cylinder of material, a carriage movable toward and from said support, a rotating knife head on said carriage, a knife movable radially of the head and into the material, a gage on said carriage

15 at the rear of the knife and adapted to contact the support, and means to move the carriage with the knife withdrawn until the stop is operative and then to project the knife into the material.

15. 11. In a machine for cutting fan belts or the like, a support for a cylinder of material, a knife head, the support and the knife head being movable relatively to one another, means for rotating the knife head, a radially 20 movable knife on said head, a stop device to limit the approach of the material and the knife head, and means to project the knife into the material.

12. In a machine for cutting belts or the like, a cylinder for exteriorly supporting a cylinder of material, a continuously rotating knife head movable on the axis of the material on said support to a position interiorly thereof, a knife, and means for projecting 25 the knife into the material on said support while the head is being rotated.

13. In a machine for cutting belts or the like, a cylinder for exteriorly supporting a cylinder of material, a continuously rotating 30 knife head movable on the axis of the material on said support, a stop to limit the movement of the head in a position within the cylinder on said support, a knife radially movable of the head, and means to retain the 35 knife in a position within the head and to project it outwardly of the head after axial movement thereof has been arrested.

14. In a machine for cutting fan belts or the like, a support for a cylinder of material, 40 and a continuously rotating knife carrier movable simultaneously in a circular path about the axis of the cylinder on said support and in a straight line along said axis,

said knife carrier being also movable radially of the cylinder on said support. 50

15. In a machine for cutting fan belts or the like, a support for a cylinder of material, a knife, means to move said knife in a circular path about the axis of the cylinder on said support, and means to move said knife 55 radially and axially of the cylinder on said support.

16. In a machine for cutting cylinders of material, a knife, a support for a cylinder, means to move said knife in a circular path 60 about the axis of the cylinder on said support, and means to move the knife selectively in an axial or radial direction of said cylinder on said support.

17. In a machine for cutting cylinders, a 65 tubular support for the exterior of the cylinder, a carriage movable to and from the support, a rotating shaft on the carriage, a stop on the carriage, a knife head carried by the shaft forwardly of said stop, a radially movable knife on said head, a cam adapted to actuate the knife, a longitudinally slideable rod connected with said cam, spring devices to normally retract the rod, and lever mechanism contacting the rod. 75

18. In a machine of the class described, means for exteriorly supporting a hollow cylinder so that it may be fed thereon, and a 80 rotary knife radially movable within said means so as to intermittently cut short cylinders from said cylinder and permit feeding of the cylinder in said means.

19. Apparatus for cutting fan belts or the like comprising a knife, a hollow cylindrical member in which a cylinder of fabric may be 85 inserted, means whereby the member and said knife may be relatively shifted the thickness of a belt to position the knife within the fabric cylinder, means for relatively shifting the knife and member to project the 90 knife into said fabric cylinder, and means for relatively rotating the knife and said member to perform the cutting operation.
